CLAIM

The ornamental design for a console for an excavator, as shown and described.

DESCRIPTION

FIG. 1 is a perspective view of a console for an excavator; FIG. 2 is a front view of the console illustrated in FIG. 1; FIG. 3 is a back view of the console illustrated in FIG. 1; FIG. 4 is a right side view of the console illustrated in FIG. 1; FIG. 5 is a left side view of the console illustrated in FIG. 1; FIG. 6 is a top view of the console illustrated in FIG. 1; and, FIG. 7 is a bottom view of the console illustrated in FIG. 1. The broken lines shown in the drawings illustrate portions of a console for an excavator that form no part of the claimed design.
